UNITED STATES PATENT OFFICE.

HOMER C. LA BATT, OF CHICAGO, ILLINOIS, ASSIGNOR TO WILLIAM J. HERRICK, OF CHICAGO, ILLINOIS.

TRIPPING DEVICE FOR PRINTING-PRESS CYLINDERS.

1,087,246.

Specification of Letters Patent.

Patented Feb. 17, 1914.

Application filed December 18, 1903, Serial No. 185,625. Renewed July 14, 1911. Serial No. 638,581.

To all whom it may concern:

Be it known that I, HOMER C. LA BATT, a citizen of the United States, residing at Chicago, in the county of Cook and State of Illinois, have invented certain new and useful Improvements in Tripping Devices for Printing-Press Cylinders, of which the following is a specification.

This invention is concerned with an automatic tripping device for paper handling machines such as printing presses.

Cylinder printing presses as generally constructed are provided with means for tripping the cylinder to throw the same out of operation when necessary or desirable, and such means are commonly controlled by the operator through the medium of a suitable lever or other connection located within convenient reach and actuated by him when no sheet is delivered to the cylinder, to prevent inking of the platen, or when there is other fault in the operation of the press and it is desired to avoid making an impression, as for example when the sheet being delivered to the press is crumpled or torn or when a plurality of sheets is simultaneously delivered to the press.

The present invention has for its object to provide mechanism for automatically operating the cylinder tripping means and which may be an adjunct to, or independent of, the usual controlling mechanism employed for this purpose.

The invention consists of the combination and arrangement of parts hereinafter described, particularly pointed out in the appended claims, and illustrated in the accompanying drawings, in which—

Figure 1 is an end elevation of the device showing the same in connection with the rear portion of the frame of a printing press; Fig. 2 is a side elevation of the tripping device on an enlarged scale; Fig. 3 is a top plan view of the same; Fig. 4 is an elevation of the end of the device opposite to that seen in Fig. 1; and Fig. 5 is a view corresponding to Fig. 2, but with the connecting arm in its inactive position.

The invention is applicable to any type of printing press in which a cylinder is employed for carrying the sheet against the form and provided with mechanism for tripping the cylinder to prevent the same from making an impression and for restoring the cylinder automatically, or in any other man-

ner, to throw the same into operative position again for a subsequent impression. As the mechanism for tripping or throwing the cylinder out of operative position and for restoring the same may be of the usual and ordinary or any preferred construction I have deemed it unnecessary to illustrate the same.

The present device is particularly adapted for use with automatic feeders for delivering the sheets to the printing press with which it is associated, and to this end may be provided with any suitable connection with an associated part or adjunct of the feeder and so arranged that upon the failure of the feeder to deliver a sheet to the cylinder, or by the delivery of a plurality of sheets or owing to any other fault in the operation of the feeder, the cylinder will be tripped. It is to be understood, however, that the device is not restricted to this particular use and that it may be operated through the medium of any suitable connection to control the device and adapted to be operated in any suitable manner.

In Fig. 1, 10 indicates the frame of an ordinary printing press, the cylinder, bed and other operative parts not being shown. Journaled in any suitable manner, as in bearings 11 carried by the frame 10, is a shaft 12. The shaft 12 may be driven from a connection with the mechanism for operating the press or in any other preferred manner. In practice I prefer to employ the shaft 12 for communicating motion from the drive shaft of the printing press to the feeding machine with which the tripping device is associated. Secured to the frame 10, or to any other suitable support, is a bracket 13. This bracket is shown in the present instance as bolted to the bottom rail of the frame 10; and mounted thereon is a movable element to which is attached the operating connection leading to the usual mechanism for tripping the cylinder. The movable element may be actuated in any preferred manner, as through the medium of the shaft 12, as hereinafter described. In the present embodiment of the invention the bracket 13 is provided on its rear face with a longitudinal way or groove 14, and the movable element takes the form of a slide 15 seated in the groove and retained by lips 16 engaging the outer face of the slide, as shown in Fig. 4. Attached at one end 110

to the slide 15 is a connection, such as the cable 17, which leads to and is adapted to actuate the means for tripping or raising the cylinder.

5 Pivoted as at 18, to the slide 15, is an arm 19, which extends outwardly from the frame 10, and is designed to be engaged in such manner as to be moved longitudinally and thereby to move the slide 15. To this
10 end there is fixed upon and rotates with the shaft 12 an element which may take the form of a disk 20 and provided with a device adapted to engage the arm to couple it to the disk and which is of such character
15 as to release the arm as soon as the cylinder has been tripped. The means for accomplishing this result may be variously embodied. In the present embodiment of the invention, the arm 19 is made substantially
20 in the form of a latch, the free end thereof being provided with a lug or hook 21 which is adapted to be engaged by a shoulder 22 of a dog 23, pivoted at 25 on the disk 20. The dog 23 is held or sus-
25 tained, during a portion of the rotation of the disk, in position to engage the latch 19, when the latter is released and moves into its active position, as by means of a cam 24. This cam in the construction shown, is rigid
30 with an arm or extension 26 which projects outwardly from the bracket 13, and such arm is provided with an aperture through which the shaft 12 passes. The cam 24 projects in the path of the inner end of the dog 23, and is so located as to be engaged
35 thereby as the dog is moving past the free or outer end of the latch. By this means the dog 23 is so held that its shoulder moves against the latch when the latter is released
40 in the manner to be hereinafter described, and, as shown in Fig. 2, carries the latch with it thereby moving the slide. As soon as the cylinder has been tripped so as to be held out of contact with the form, the dog
45 23 passes out of engagement with the cam, and, owing to the resistance of the latch and the rotation of the disk 20, is turned on its pivot so as to release its shoulder from the latch. The dog 23, after the disengagement
50 of the arm in the manner described, is returned to its normal or active position, as by means of an expansion spring 26^a attached at one end to the disk 20 in advance of the dog and at its other end to the dog
55 beyond the pivot thereof, a stop 32 fixed on the disk serving to limit the movement of the dog under the stress of such spring.

During the normal operation of the press the arm 19 is held in an inactive position, that is to say with its hook 21 out of the path of the shoulder of the dog 23, and suitable means are provided for holding it in this position as well as for releasing the holding means when it is desired or necessary to trip the press cylinder.

In the present embodiment of the invention I show an electromagnet for accomplishing the result, although any other suitable means may be employed. The electromagnet 27 may be mounted on the bracket 13 above the arm 19 and have its armature 28 pivoted at its upper end, as at 29, so as to depend in the position shown in Fig. 2. The end of the armature in its normal position, that is when the magnet is deenergized, projects in the path of and is engaged by a toe or extension 30 at the rear end of the arm 19, and when the parts are in this position the armature serves as a lock for the arm and holds it with its outer or hooked end elevated out of the path of the shoulder of the dog 21, as shown in Fig. 5. The armature is normally retained in and returned to its locking position upon the deenergization of the magnet by a spring 31. 70 75 80 85

Upon the energization of the magnet 27 its armature 28 is attracted, withdrawing its end from engagement with the toe 30 of the latch 19, which then drops, as by gravity, so as to have its hook 21 lowered into the path of the shoulder on the dog 23, the latter at this point in the cycle of operations of the press having been moved up so as to engage the hook immediately after the latter drops into its path and being held in its active position by the cam 24. The arm or latch is then pulled along by the dog 23 which, as soon as the tripping mechanism is operated, is released by the movement of the dog away from the cam 24 so that the cylinder may be restored to operative position in the usual manner. 85 90 95 100

In the present instance I have shown a push button 33 in the circuit of the electromagnet 27 for energizing the latter, but it is to be understood that this is employed simply for the purpose of illustrating the operation of the device. In practice I prefer to energize the electromagnet by means of a device or devices controlled by the paper fed to the press. This control may be of any suitable or preferred character, as will be well understood by those skilled in the art, and need not be further explained. 101 110

Means are preferably provided for automatically resetting the arm or latch 19 after its release by the dog 23. The mechanism for accomplishing this result may be of any suitable form adapted to the attainment of the desired end. In the present instance the disk 20 is provided with a cam portion 34 on its periphery which is so located as to elevate the outer end of the arm 19 and restore it to its normal position as the arm becomes disengaged from the dog 23. The arm 19 is provided with an offset located in the plane of rotation of the disk, and the offset preferably takes the form of an anti-friction roller 35. When the cam portion 34 of the disk engages the roller 35 the arm 19

is lifted so that its toe 30 is moved out of the path of the end of the armature which, assuming the electromagnet to have been de-energized by the opening of the circuit, is retracted by its spring and engages the toe to hold the arm in its inactive position ready to be released by the closing of the circuit again.

A stop 36, fixed on the bracket 13 at the rear of the armature 28, serves to limit the movement of the armature on the retraction of the same by the spring 31, and a similar stop 37 may be provided to limit the upward movement of the arm 19 when raised by the cam 34.

What I claim as new and desire to secure by Letters Patent is—

1. In a device of the class described, the combination with a connection for operating the tripping mechanism of a paper handling machine, of means for actuating the connection and comprising a rotating element, and a latch adapted to be automatically coupled thereto.

2. In a device of the class described, the combination with the connection for actuating the tripping mechanism of an operating paper handling machine, of rotating means for moving the connection, a latch for automatically coupling the moving means with the connection, and means for uncoupling the latch.

3. In a device of the class described, the combination with the connection for actuating the tripping mechanism of a paper handling machine, of a movable element to which the connection is attached, an arm pivoted on the element, a rotatable element, and means for detachably coupling the arm to the rotatable element.

4. In a device of the class described, the combination with the connection for actuating the tripping mechanism of a paper handling machine, of a movable element to which the connection is attached, an arm pivoted on the element, a rotatable element, means for coupling the arm to the rotatable element, and means for uncoupling the parts.

5. In a device of the class described, the combination with the connection for actuating the cylinder tripping mechanism of a printing press, of a slide to which the connection is attached, a latch pivoted to the slide, a rotatable element, and means for coupling the latch to the rotatable element.

6. In a device of the class described, the combination with the connection for actuating the cylinder tripping mechanism of a printing press, of a slide, a latch pivoted to the slide, a rotatable element, means for coupling the latch to the element, and means for uncoupling the parts.

7. In a device of the class described, the combination with the connection for actuating

ing the cylinder tripping mechanism of a printing press, of a slide to which the connection is attached, a latch pivoted on the slide, a rotatable disk, means carried by the disk to engage the latch, and means to hold the latch out of such engagement.

8. In a device of the class described, the combination with the connection for actuating the cylinder tripping mechanism of a printing press, of a slide to which the connection is attached, a latch pivoted on the slide, a rotatable disk, means carried by the disk to engage the latch, means to disengage the latch, and means to hold the latch out of such engagement.

9. In a device of the class described, the combination with the connection for actuating the cylinder tripping mechanism of a printing press, of a normally inactive latch movable with the connection, means for engaging the latch to move the connection, means for disengaging the latch, and means for automatically restoring the latch to its inactive position.

10. In combination with the operating connection of a press cylinder tripping device, of a normally inactive latch movable with the connection, and means provided with a dog for engaging the latch to move the connection, and a cam to hold the dog in engagement with the latch.

11. In combination with the operating connection of a press cylinder tripping device, of a latch movable with the connection, a disk having a dog to engage the latch to move the connection and then to release the latch, and a device for restoring the latch.

12. In a device of the class described, the combination with the connection operating the mechanism for tripping a printing press cylinder, of a slide to which the connection is attached, a normally inactive latch carried by the slide, means for holding the latch in its inactive position, means for releasing the latch, a rotating disk, a dog carried by the disk and adapted to engage the latch when the latter is released, and a cam to hold the dog in engagement with the latch.

13. In a device of the class described, the combination with the connection for operating the mechanism for tripping a printing press cylinder, of a slide to which the connection is attached, a normally inactive latch pivoted on the slide, a pivoted device for engaging the latch to hold the latter in its inactive position, means for releasing the pivoted device, a rotating disk, a dog pivoted on the disk and adapted to engage the latch when the latter is released, a fixed cam engaging the dog to hold it in engagement with the latch during a portion of the rotation of the disk, and a cam on the disk to restore the latch when released by the dog.

14. In a device of the class described, the combination with the normally inactive

latch, means for holding the latch in its inactive position, electromagnetic means for moving the holding means to release the latch, and a rotatable element for engaging 5 the latch to move the latter when released.

15. In a device of the class described, the combination with the normally inactive latch, means for holding the latch in its inactive position, electromagnetic means for 10 moving the holding means to release the latch, a disk, and a dog carried by the disk to engage the latch when the latter is released.

16. In a device of the class described, the combination with the normally inactive latch, an electromagnet provided with an armature engaging the latch to hold it in its inactive position, means for energizing the magnet to withdraw the armature from 20 its holding position, a rotating disk, and a dog pivoted on the disk and adapted to engage the latch when the latter is released.

17. In a device of the class described, the combination with the normally inactive 25 latch, an electromagnet provided with an armature engaging the latch to hold it in its inactive position, means for energizing the magnet to withdraw the armature from

its holding position, a rotating disk, and a dog pivoted on the disk and adapted to engage the latch when the latter is released, 30 means for holding the dog in engagement with the latch during a portion of the rotation of the disk, and means for restoring the latch upon the disengagement of the 35 dog.

18. In a device of the class described, the combination with the normally inactive latch, an electromagnet provided with an armature engaging the latch to hold it in 40 its inactive position, means for energizing the magnet to withdraw the armature from its holding position, a rotating disk, and a dog pivoted on the disk and adapted to engage the latch when the latter is released, 45 a cam for holding the dog in engagement with the latch during a portion of the rotation of the disk, and a cam acting on the arm for restoring the latch upon the disengagement of the dog. 50

In testimony whereof I affix my signature in presence of two witnesses.
